HAIR CLIPPER

John A. Hanley, Noroton, Conn., assignor to Clip-shave Inc., Port Chester, N. Y., a corporation of New York

Application April 5, 1937, Serial No. 134,986

19 Claims. (Cl. 30—43)

My present invention relates to hair clipping apparatus and is more especially concerned with apparatus of the above type for use as a razor in clipping hair stubble, although it is useful also for shearing longer hair. The invention constitutes an improvement on my prior applications Serial No. 739,432 filed August 11, 1934 on which Patent No. 2,077,367 was granted on April 13, 1937 and Serial No. 5319, filed February 7, 1935 on which Patent No. 2,102,529 was granted on December 14, 1937 and accomplishes all of the fundamental objects of said prior applications.

Among other objects of the invention are to provide a clipping head for a device of the above type, easily applied by resort to a single thrust for cooperative relation with respect to the carrying handle and the motor thereof, and without the need for auxiliary latching plates or mounting screws that might exert distorting stresses upon the clipping instrumentalities, and inherently affording protection to the user against the possibility of abrasion.

A further object is to provide a clipping head of the above type in which the pressure exerted in use is localized with greater effectiveness along the region at which the clipping actually occurs, without likelihood of applying frictional load over a wider area.

In the accompanying drawing in which is shown one of various possible embodiments of the several features of the invention:

Fig. 1 is a plan view of the clipping head with parts broken away to show the inner plate,

Fig. 2 is a fragmentary side elevation of the mounted clipping head,

Fig. 3 is a transverse sectional view taken along line 3—3 of Fig. 1,

Fig. 4 is a transverse sectional view on a greatly enlarged scale taken on line 4—4 of Fig. 1,

Fig. 5 is a fragmentary view on a larger scale of a detail of the outer or sheathing plate prior to inturning the latter, and

Fig. 6 is a cross sectional view taken on line 6—6 of Fig. 4.

Referring now to the drawing, there is shown the general outline of a desirable form of insulating handle 10, which serves as a casing to house a suitable electric motor for oscillating the operating lever 11, the extremity 12 of which protrudes through a corresponding port 13 in the reduced forward end of the casing. The motor (not shown) is preferably of the type of that shown, described and claimed in my copending application Serial No. 757,755, filed December 17,

1934, although any other suitable motor may be employed.

The clipping head, in common with that of my prior Patent No. 2,102,529 includes an outer shear plate 14 having flanges 15 turned under the serrated or toothed edges 16 of the inner plate 17 and sheathing the latter and has resilient latch means for mounting the assembly to the casing with said inturned flanges held against the casing end 10. In common with said earlier case 10 the serrations on the inner plate present shearing faces and the gaps between said serrations afford widened hair shedding gaps at the area below the shearing conformation and the outer or fixed plate is slotted to present shearing conformations and shedding ports. Also in common with said earlier application the two plates are preferably of stainless steel, the moving or inner plate being preferably of stock of .015" to .020" in thickness and the outer plates may be 20 of resilient steel stock of from .008" to .010" in thickness.

The inner shear plate is preferably undercut, that is, the under or non-shearing area of the plate is of smaller width than the outer or shearing face thereof, the edges being beveled as at 18, the forward ends of the teeth 16 being relatively sharp. The lateral walls of each tooth of the inner plate converge from the outer to the inner face thereof as appears at 19 in Fig. 6, to afford a lateral flare of the interdental spaces from the clipping to the shedding face thereof, and are longitudinally undercut at the troughs as at 20 (Fig. 4).

The slots in the fixed or outer shear plate 14, as best shown in Fig. 5, are spindle-shaped, being preferably formed by means of formed milling cutters (not shown) to afford openings 21 of length and width considerably less at the inner face than the corresponding openings at the outer face, the walls of the slots shown at 22 extending through the thickness of the plate. The blank shown in Fig. 5 has inturned lateral flanges 15 extending about the beveled margins of the inner plate to afford clearance as at 23 with respect to the points of teeth 16 and clearance as at 24 with respect to the entire area of the beveled edge 18, the inturned flange being curved as at 25 for that purpose and being reversely curved therebeyond as at 26 for resilient engagement as at 27 with the under face of the inner plate. The fold edge 28 of the outer plate is nearer the inner than the outer ends of the slots or notches so that as best shown in Fig. 4, the inturned portions of slots 22 which extend 55

transversely of the inturned flanges 15 of the outer plate extend substantially the full width of the beveled edges 18 of the inner plate and afford hair shedding gaps exposing the entire 5 length of the undercut interdental spaces at the under face of the inner plate. The upper portions of slots 22 along the face of the plate 14 extend along the entire length of the shear teeth 16 on the upper face of the plate 17.

10 As best shown in Fig. 4, the upper ends 22^u of the slots 22 slope away from the troughs of the interdental spaces of the inner plate 17 and the lower or inner ends of the slots 22 extend outward from the undercut troughs 20 of the 15 interdental spaces, as at 22^l.

By reference to Fig. 6, it will be seen that as a consequence of the obliquely cut walls of teeth 16 and of slots 22, the lateral walls of said slots converge from the outer to the inner face of the 20 outer plate 14 and the lateral walls of each tooth 16 of the inner plate converge at 19 from the shearing to the shedding face thereof, while the slots 22 along the inturned flanges 15 diverge laterally.

25 Accordingly there are relatively wide entry ports for the hair at the upper face of plate 14, and the clippings pass through the surface of contact between the teeth 16 and slots 22 where the clipping occurs, to be readily shed through 30 the longitudinally and laterally diverging interdental spaces of plate 14 and the similarly diverging walls of slots 22, for prompt discharge from the apparatus, without likelihood of clogging.

35 As shown in the drawing, the body of the outer plate 14 between the inner ends 22^u of the shearing slots thereof is convex or crowned as at 30, away from the inner plate to localize at the margins the pressure to be applied thereat in shearing. The metal of the main expanse of the 40 outer plate is preferably thinned by grinding at its clipping margins as at 31, to afford enhanced resiliency thereat due to the resiliently applied pressure transmitted from the crowned or bowed region 30, for effective snug engagement with the 45 teeth 16 of the inner plate 14.

According to the present invention the inner shear plate 17 has rectangular tongues 33 struck out of the stock thereof, affording openings 34, 50 said tongues extending downward between the inner edges of the inturned flanges 15 of the outer plate and preferably in sliding engagement therewith as at 35. One of the functions of these tongues is to guide the reciprocating movement of the inner plate with respect to said flanges and therefore with respect to the outer plate 14 for effective shearing coaction. The points of the teeth 16 of the inner plate thus remain uniformly spaced from the folded edges 55 28 of the outer plate, as at 23. The tongues 33 extend into corresponding rectangular depressions 36 in the end of the handle casing, which depressions afford guideways therefor to assure rectilinear reciprocating movement of the inner plate 17, in the operation of the motor, without 60 any tendency to tilt or bind with respect to the outer plate.

65 For affixing the shearing head to the handle casing, improved resilient latch means are preferably provided. In the specific embodiment shown, the latch means comprise clip members 37 each of generally stave shape and of resilient metal, extending transversely across the respective ends of the outer or fixed plate 14 each being 70 affixed to said plate near its center as at 38 and 75

having its protruding ends 39 down-turned, and curved inwardly to latch over corresponding narrow shoulders 40 molded at the corresponding parts of the casing.

The clipping edges of the shearing head extend 5 laterally beyond the casing but are preferably shielded by said casing, at their end edges. For that purpose, the casing has upstanding end ledges 41 substantially flush with the plane of the shearing head interposed therebetween but 10 the gaps between said head and said ledges are bridged by the central strap portion of the respective clips 37, to guard against the entry of hair thereinto.

As it is preferred to spot weld the mounting 15 clip to the outer plate and as, in view of the narrowness of such clip it might be difficult to accomplish this effectively and yet have part of the width of the clip extend sufficiently beyond the plate to lap over the ledges 41, the outer 20 plate is preferably provided with short extensions 42 beyond the ends of the inturned flanges 15. The outer edges of the clips 37 are brought flush with the free edges of the respective extensions 42 so that spot welding as at 38 may be effected 25 midway between the lateral edges of the clips.

It is seen that the clipping head assembly is readily applied to the carrying handle by simply superposing it thereover between ledges 41 and permitting the clip ends 39 resiliently to snap 30 over the corresponding shoulders 40 on the handle. The mounting can thus be effected substantially by a single thrust, in which operation the inner plate is effectively brought by its guide tongues 33 into effective position upon the handle 35 10, with the operating lever end 12 extending into the central aperture 44 of plate 17, and the strips 37 are brought into effective bridging relation over the protective ledges 41 on the handle casing.

The inner plate 17 is resiliently pressed by 40 flanges 15 against the outer plate 14 for snug contact at the marginal or clipping region. The handle end takes the pressure applied in use by the engagement of flanges 15 therewith, and such pressure tends to enhance the snugness of engagement at the shearing margins. The pressure applied in use is necessarily localized at said marginal regions and at the tangential flange portion 50 27, for effective operation with a minimum of load on the motor. By reason of the widening area of the shedding instrumentalities there is no likelihood of clogging of the shearing teeth with 55 clippings and the device need not be frequently taken apart for cleaning. By reason of the central mounting of the resilient latching clips, no 60 distorting pressure is applied to the clipping plates, the coaction of which at the superposed clipping teeth is in no way impaired by distortion or otherwise, as it might be if substantial localized pressure were applied in such mounting.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be 70 made without departing from the scope thereof, it is intended that all matter contained in the above description or shown in the accompanying drawing shall be interpreted as illustrative and not in a limiting sense.

Having thus described my invention, what I claim as new and desire to secure by Letters Patent is:—

1. In a hair clipping apparatus of the type comprising an inner serrated plate and an outer plate having an inturned flange sheathing the serrated plate and slotted to form shearing teeth coacting with those of said serrated plate; the combination in which the shearing coaction between the two plates is localized at the margins thereof, in which the sheathing flange is curved for resilient engagement with the under face of the inner plate and in which the outer face of the inner plate is free from engagement with the outer plate beyond the shearing margins of contact.

2. A hair clipping head comprising a toothed reciprocating inner plate having a shearing face, an edge inwardly bevelled therefrom and presenting hair shedding ports through the interdental spaces at the bevelled edge and at the under face thereof, a coacting fixed shearing plate having an inturned flange enclosing the serrated edge and slotted for clipping coaction with said teeth, said outer plate engaging the inner plate at said slotted regions, said inturned flange being curved for resilient engagement with the under face of said inner plate, said plates being free from engagement with each other at areas other than the recited areas of contact.

3. A hair clipping head comprising a generally rectangular inner plate having shear teeth therethrough along its opposite edges, said plate providing hair shedding interdental spaces at the under face thereof, an outer plate having inturned flanges enclosing the toothed edges of the inner plate, said flanges being slotted across the respective bases thereof, to afford shearing edges at the main area thereof coacting with those of the inner plate and to afford hair shedding ports coacting with the shedding spaces of said inner plate, said flanges being curved for resilient engagement with the under face of the inner plate to hold said inner plate resiliently against the outer or shearing face of the outer plate.

4. A hair clipping head comprising an inner plate having shear teeth therethrough along its opposite edges, said plate providing hair shedding interdental spaces at the under face thereof, an outer plate having inturned flanges enclosing the toothed edges of the inner plate, said flanges being slotted across the respective bases thereof to afford shearing edges at the main area thereof coacting with those of the inner plate and to afford hair shedding ports coacting with the shedding spaces of said inner plate, the under face of said inner plate being resiliently engaged by said flanges and the outer face of said inner plate being held against the outer or shearing face of the outer plate, the outer plate being bowed away from the inner plate through the width thereof between the shearing lengths of the slots therein.

5. A hair clipping head comprising a flat generally rectangular inner plate having shear teeth therethrough along its opposite edges, said plate providing hair shedding interdental spaces at the under face thereof, an outer plate having inturned flanges enclosing the toothed edges of the inner plate, said flanges being slotted through the respective bases thereof to afford shearing edges at the main area thereof coacting with those of the inner plate and to afford hair shedding ports coacting with the shedding spaces of said inner plate, said inner plate being resilient-

ly held by said flanges against the outer or shearing face of the outer plate, the inner plate having its edges bevelled inward from the cutting to the shedding face thereof to present at the outer face thereof relatively sharply pointed teeth 5 guarded by said inturned flanges.

6. A hair clipping head comprising a flat generally rectangular inner plate having shear teeth therethrough along its opposite edges, said plate being undercut to provide hair shedding interdental spaces at the under face thereof, an outer or fixed plate having inturned flanges enclosing the toothed edges of the inner plate, said flanges being slotted across the respective bases thereof to afford shearing edges at the main area thereof 10 coacting with those of the inner plate and to afford hair shedding ports coacting with the shedding spaces of said inner plate, said inner plate being resiliently held by said flanges against the outer or shearing face of the outer plate, the 15 lateral edges of the outer plate being bevelled at the portions thereof registering with said shedding ports.

7. A hair clipping apparatus comprising a handle member, a shearing head removably mounted 25 thereon, said head comprising an inner shear plate having serrations therethrough at its edge and presenting at said serrations a shearing face and a shedding face, said plate having median tongues extending inward therefrom and lodged 30 in guiding depressions of corresponding width in the forward end of said handle, an outer plate having clipping conformations coacting with the shearing faces of said serrations, and resilient latch means for attaching said outer plate to said 35 handle with said inner plate guided by said tongues, for reciprocation in resilient contact with said outer plate.

8. A hair clipping head comprising an inner plate serrated at one edge thereof, said serrations 40 extending through the thickness of said plate and affording shearing edges at one face thereof and hair shedding gaps at the other face thereof, an outer shear plate superposed over and having a flange embracing the serrated edge of the inner plate, said outer plate being slotted across 45 the embracing edge thereof to afford shearing edges coacting with those of said inner plate, and tongues struck inward from the inner plate and protruding downward beyond the flange of the 50 outer plate for coaction with corresponding guides in a handle.

9. A hair clipping head comprising an inner plate serrated at one edge thereof, said serrations extending through the thickness of said plate 55 and affording shearing edges at one face thereof and hair shedding gaps at the other face thereof, an outer shear plate superposed over and having a flange embracing the serrated edge of the inner plate, said outer plate being slotted across 60 the embracing edge thereof to afford shearing edges coacting with those of said inner plate, and means for positioning said head with respect to a handle, said means comprising tongues struck inward from the inner plate and protruding downward beyond the flange of the outer plate for coaction with corresponding guides in the handle, said tongues engaging the edge of 65 said inturned flange.

10. A hair clipping apparatus comprising a 70 motor enclosing handle casing, a hair clipping head removably mounted on the end of said casing, said head comprising the assembly of an inner shear plate having serrations along its opposite edges presenting shearing edges at one face 75

thereof and hair shedding gaps at the other face thereof and an outer plate having inturned flanges embracing said serrated edges, said outer plate being slotted to present shearing and shedding conformations in registry with those of the inner plate, tongues struck inward from said inner plate and extending between the flanges of the outer plate and in contact with the edges of the latter into corresponding guideways at the 5 end of the handle, operating means extending from said motor through the end of said handle into a corresponding central aperture in the inner plate for reciprocating the latter in a movement guided by the coaction of said instruck 10 tongues and said handle end and resilient latch means releasably mounting said outer plate upon 15 said handle casing.

11. The combination recited in claim 10 in which the latch means comprises downwardly 20 extending tongues unitary with the outer plate and latched over corresponding shoulders on the handle casing.

12. A hair clipping head assembly comprising inner and outer shear plates, the latter having 25 lateral flanges embracing the edges of the former, the inner plate having serrations and the outer plate having slots to afford coacting shear edges and coacting shedding ports, the inner plate having protruding conformations unitary therewith to position the latter and the outer plate 30 having lateral resilient tongues unitary therewith and protruding downward from near the ends thereof for latching connection to a carrying handle.

13. A hair clipping head assembly comprising 35 inner and outer shear plates, the latter having lateral flanges embracing the edges of the former, the inner plate having serrations and the outer plate having slots to afford coacting shear 40 edges and coacting shedding ports, the inner plate having protruding conformations unitary therewith to position the latter, the outer plate having resilient mounting clips affixed to the ends thereof, presenting lateral 45 downwardly extending resilient tongues for latching attachment to a handle.

14. A hair clipping head assembly comprising inner and outer shear plates, the latter having 50 lateral flanges embracing the edges of the former, the inner plate having serrations and the outer plate having slots to afford coacting shear edges and coacting shedding ports, the inner plate having protruding conformations unitary therewith to position the latter, and mounting 55 clips extending transversely across the ends of the outer plate, affixed thereto near the middles thereof and presenting downwardly extending resilient tongues adapted to be latched to a handle.

15. A hair clipping head assembly comprising 60 inner and outer shear plates, the latter having lateral flanges embracing the edges of the former, the inner plate having serrations and the outer plate having slots to afford coacting shear 65 edges and coacting shedding ports, the inner plate having protruding conformations unitary therewith to position the latter and clip

members comprising strips of resilient metal extending transversely across the respective ends of the outer plate and permanently affixed at their middles centrally of the respective ends of the outer plate and presenting down-turned tongues for resilient latching engagement to a carrying handle. 5

16. In a hair clipping head, the combination of an outer fixed plate of thin sheet metal stock presenting lateral shearing conformations, said plate having a short central extension at each end thereof beyond said shearing conformations, mounting clip strips of resilient metal extending at their outer edges along said extensions, said strips being spot welded at their respective 10 middles midway of the widths of said extensions, each of said strips presenting downturned resilient ends for mounting on a carrying handle. 15

17. A hair shearing apparatus comprising an insulating casing having an electric motor therein with an operating reciprocating lever protruding through a corresponding port in one end of said casing, a clipping head assembly 20 removably mounted upon the end of said casing and presenting an inner plate and an outer plate, the latter having inturned flanges extending about the edges of the former, the inner plate being serrated and the outer plate being slotted at the inturned edges thereof to afford coacting 25 shearing edges and coacting shedding ports, said inner plate having a central aperture fitted over the end of the operating lever end, the inner plate having down-struck tongues extending into corresponding guideways in the end of the handle casing, the clipping conformations 30 of said head extending beyond the lateral surface of the handle casing, said casing having integral upstanding ledges confining the ends of the clipping assembly therebetween and means for resiliently latching said assembly to 35 said handle casing, said means comprising resilient mounting clip pieces extending across the 40 ends of the outer plate, affixed thereto, and bridging the gaps between said ledges and said clipping head assembly, said clips having downwardly extending resilient ends and said casing 45 having shoulders over which said ends are resiliently latched. 50

18. The shearing apparatus as claimed in claim 17 in which the outer plate has narrow 55 extensions interposed between the tops of the respective ledges and the mounting clips which are centrally spot welded thereto.

19. A hair clipping head comprising an inner plate having shear teeth along its lateral edges and an outer plate having inturned flanges embracing said toothed edges and transversely slotted to afford shearing edges coacting with those of said teeth, said flanges having parallel edges facing each other, and downwardly extending lugs rigid with said inner plate extending between and engaging said flange edges and serving to retain said inner plate in symmetrical relation with respect to said outer plate with the points of the teeth uniformly spaced from the fold edges of said outer plate. 60 65

JOHN A. HANLEY.
